(57) **CLAIM**

We claim the ornamental design for a blender assembly, as shown and described.

DESCRIPTION

FIG. 1 is a front top perspective view of a blender assembly of the present disclosure;

FIG. 2 is a rear top perspective view of the blender assembly of FIG. 1;

FIG. 3 is a front elevational view of the blender assembly of FIG. 1;

FIG. 4 is a rear elevational view of the blender assembly of FIG. 1;

FIG. 5 is a first side elevational view of the blender assembly of FIG. 1;

FIG. 6 is a second side elevational view of the blender assembly of FIG. 1;

FIG. 7 is a top plan view of the blender assembly of FIG. 1; and,

FIG. 8 is a bottom plan view of the blender assembly of FIG. 1.

The broken lines depict portions of the article that form no part of the claimed design.

1 Claim, 8 Drawing Sheets
